KNOCKDOWN BARREL.

1,142,269.

Specification of Letters Patent.

Patented June 8, 1915.

Application filed March 28, 1911. Serial No. 617,358.

To all whom it may concern:

Be it known that we, DANIEL R. PRUDEN, of Revere, in the county of Suffolk, and DANIEL W. WORMWOOD, of Chelsea, in the 5 county of Suffolk, both in the State of Massachusetts, have jointly invented certain new and useful Improvements in Knockdown Barrels, of which the following is a specification.

10 This invention is designed to meet and satisfy a long felt want by providing a sensible and practical shipping package in barrel form, especially adapted, without dismemberment, to fold flat and most compactly for return and repeated reshipment.

Our knock-down barrel is of substantially cylindrical form,—that is, while composed of a succession of narrow, flat connected staves with suitable heads and fastenings, it 20 is destitute of the usual bilge so that its area at each end is the same as at the center, thus giving greater capacity to a railroad car, filled with such barrels. Furthermore the hoops are not removed or the head mutilated when our improved barrel is opened,— 25 a feature of much importance in a collapsible barrel. We provide also a peculiar closure and sample opening on one of the heads for inspection of the contents of the barrel, and 30 means for tightening the fastenings after it is fully packed. The staves are transversely connected by flexible bands having terminal fastenings, and, as here shown, are arranged in successive sections united by hinges in 35 the bands at the folding points, the terminal section edges only having such fastenings.

In the drawing, Figure 1 is a side view, Fig. 2, a vertical section and Fig. 3 an end view. Fig. 4 is a top or side and Fig. 5 an 40 end view of the barrel folded inside out. Figs. 6 and 7 represent details hereinafter explained.

As best seen in Figs. 1 and 3, the staves 10 are severally secured in position, at their 45 ends and intermediately, by flexible bands 11, preferably of galvanized iron or steel, secured to each stave by a short wire nail or staple. The edges of the staves converge toward the axis of the barrel, see Fig. 3 where 50 they are seen held by the hoop or band 11 in close lateral contact, forming two complete arches. Figs. 1, 3 and 5 also show, at 12, the adjustable fastening devices, for engaging and disengaging the ends of the bands to 55 bring the edges of the terminal staves into

contact. In the construction shown the band ends are bent outwardly or furnished with terminal catches, one adapted to hold a screw nut from rotation while the opposing member is perforated to receive loosely the 60 threaded stem of a screw bolt engaging said nut and adapted to be tightened and loosened by a screw driver or other tool. Any equivalent device which will draw and hold the terminal staves closely together and permit 65 ready detachment may be substituted. When the upper two or three fastenings are disengaged the upper barrel head may be detached and the contents removed. The beveled edges of the barrel heads 13 enter the 70 transverse grooves 14 formed for them across the inner faces of the staves, see Figs. 2 and 4. When all the fastenings are released the entire series of staves connected by the bands may open out and lie flat on 75 the floor, a dozen or more of them superposed occupying but little space vertically, the heads making a separate compact package or being crated with them. Beside saving the cost of hinges this knock-down form 80 is best adapted for large shipments, being more speedily packed.

Our invention, however, also contemplates folding each barrel complete, by itself. To this end we arrange the staves in a plurality of foldable sections, each band being hinged at the folding line so that the staves of that section can fold outwardly and flat against or in near contact with the adjacent section, as best shown in Fig. 5. Fig. 3 illustrates 85 also the preferred arrangement, the 4 hinges 15 connecting the five sections, one midway section (which we term the back or base 16) consisting of a single stave and the length of bands which span it. The object of this back or base is to afford space, between the sections hinged to the back, for the terminal sections to fold inwardly and also for the barrel heads 13. Dotted lines in Fig. 4 indicate an oblique position of the semi-circular 90 head parts, so placed as not to project beyond the connected staves. When these staves are arranged in three sections, besides the back 16, even circular heads would be 95 completely inclosed and the package reduced in thickness. The back may be omitted and but a single row of hinges employed, the two sections folding flat, back to back, and the heads being external thereto. When 100 two barrels so made are packed together the 105 110

four heads, preferably placed cornerwise, may be inclosed between the two rectangular bodies of connected staves, transversely arranged, the two occupying less than twice 5 the space for one.

The hinges 15, best shown in Figs. 3 and 6, are preferably formed of elongated wire rings through which pass loops formed at the ends of each section of the bands 11, 10 their inward ends being drawn closely around the wire and preferably riveted. Only sufficient looseness for the folding movement is allowed. Other forms of 15 hinges, suitably secured to said bands may be employed, as we make no claim to this particular construction.

A special feature of our invention, illustrated in Figs. 2, 3 and 7, is applied to the upper head for convenience in opening and 20 closing the barrel. Instead of two semi-circular head-pieces with doweled central connection, as in dotted lines Fig. 4, we form the upper head in three members, the middle member 17, fitting snugly between 25 those on each side of it when they are engaged in the edge groove 14. This middle member is formed of two pieces united centrally by a hinge 18, on their under side, so that, when bent upwardly at the middle and 30 the beveled ends of these pieces entered in groove 14, the members 17 may be pressed down to horizontal position, closing the opening completely. One of the hinged parts of this middle member 17 has, rigidly 35 secured to its top, a locking bar 19 which extends well beyond the hinged point and there has effective locking means, here shown as screws 20 through bar 19 and entering part 17. When thus fastened the bar 40 19 reinforces the hinged member 17 against external or internal pressure, and when released it forms a substantial lever for re-

moving said member upwardly and opening the barrel.

When these barrels are designed for shipping coarse articles, such as vegetables or fruit, requiring ventilation, the staves may be spaced somewhat apart and their edges need not converge; but for flour, rice, sugar and the like the construction shown in Fig. 50 45 5 should be followed.

Our barrels being cylindrical and smooth inside, proper paper linings may be formed by one or two coils cut of proper length 55 from the ordinary wide rolls.

Safety seals of any desired form may be applied to guard against tampering with the line of fastenings for the flexible bands or with the special closure or sample-opening 60 in the upper head of the barrel.

We claim as our joint invention:

The described improvement in barrels consisting of a circular head having three contiguous members all engaged peripherally in the croze of the staves but otherwise 65 unsupported, the middle member being formed of two abutting sections united by an underneath hinge closing by an upward movement, in combination with a locking bar extending along the top of said middle 70 member, rigidly secured to one section thereof and, beyond the hinge-joint, provided with removable fastenings, such bar thus, when fastened, reinforcing the middle member and when released forming a lever for 75 removing it upwardly and opening the barrel, substantially as set forth.

In testimony whereof we have affixed our signatures, in presence of two witnesses.

DANIEL R. PRUDEN.

DANIEL W. WORMWOOD.
